UNITED STATES PATENT OFFICE.

AGÉNOR MARCHANT, JR., OF FOURMIES, FRANCE.

AUTOMATIC DEVICE WITH LIMITED FEED FOR THE SUPPLY OF INTERNAL-COMBUSTION ENGINES.

Application filed February 20, 1922. Serial No. 537,976.

To all whom it may concern:

Be it known that I, AGÉNOR MARCHANT, Jr., a citizen of France, and a resident of Fourmies, Nord, France, have invented certain new and useful Improvements in Automatic Devices with Limited Feed for the Supply of Internal-Combustion Engines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention relates to an apparatus for the supply of a fuel mixture to an internal combustion engine.

One of the principal objects of the invention is to supply a limited amount of fuel at each suction stroke of the engine, this result being obtained by limiting the amount of carburant which can be withdrawn at each suction stroke of the engine.

The invention further comprises means whereby the air can be admitted, to be mixed with the carburant, in order to form the fuel mixture.

My apparatus can be substituted to advantage for the known types of carburetors, and the fuel consumption can thus be reduced.

The following description and appended drawings, which are given by way of example, set forth the invention.

Figure 1 is a general view of the apparatus according to my invention, in elevation and in partial section, adapted for an internal combustion engine.

Fig. 2 is a section on the line 2-2 of Fig. 1.

Fig. 3 is a section on the line 3-3 of Fig. 1.

The apparatus comprises two elements, whereof one serves for the admission of fuel, and is shown in section in Fig. 2, and the other serves for an air inlet, as shown in section in Fig. 3; both elements are connected with a conduit *f* leading to the suction conduit of an internal combustion engine, *c*, Fig. 1.

The element used for fuel feed consists, as shown, in Fig. 2, of two tubes perpendicularly arranged and forming a T-shaped device, the vertical tube *b* being connected by the conduit *d*, secured to said tube by the

nut *n*, with the inlet conduit *f*: the fuel inlet duct *c* communicates with the middle part of the tube *b*, the end of said tube being closed by the screw cap *m*. Within the chamber formed by the said tube is disposed a piston *j* to which is secured the valve *i* whose stem traverses the said piston and is held in place by the nuts *k*, *k'*. The said valve cooperates with a valve seat formed within the tube at the upper part, the said valve being urged upon its seat by a spring *l* bearing at one end upon an internal shoulder of said tube and at the other end upon the piston *j*.

The horizontal tube *a*, Fig. 2, of said fuel feed element communicates with the said vertical tube *b* through the orifice *o*, the outer end of the tube *a* being closed by a screw cap *p*. Within the latter tube is disposed the piston *g* having secured thereto the rod *h* which extends through the center of said screw-cap and outwardly from the tube *a*, and is provided upon the outer portion with the shoulder *h'*; a spring *q*, which bears at one end upon said screw-cap and at the other end upon said shoulder, urges the piston *g* towards the left of Fig. 2, the motion being limited by the chain *r* secured at one end to the tube *a* and at the other end to a ring *r'* which is movable along the rod *h* and can be held in various notches *r''* spaced along the rod.

The element used for the admission of air, oxygen, or like comburent, consists of a cylindrical conduit *s*, whereof one end is closed and the other connected with the suction conduit *f*, the screw-cap *z* serving to couple the said conduit with the open end of the tube *s*. Around the periphery of the latter are spaced apertures *t*, Figs. 1 and 3. Within the tube *s* is slidable the hollow cylinder *u* having the ports *v*, cooperating respectively with the said apertures, the said cylinder having secured thereto the square or polygonal rod *w* which is slidable in a guide piece *x* of suitable shape, disposed at the coupling point of the tube *s* and the conduit *f*. A spring *y* bears at one end upon the arms connecting the guide piece *x* with a washer *x'* held between the tube *s* and said screw-cap, and at the other end upon the bottom of the cylinder *u*; said spring urges the cylinder *u* against the bottom of the tube *s*. The orifice *A* serves to connect the bottom of the tube *s* with the atmosphere.

when the cylinder *u* is raised. A sleeve *B* may be mounted upon the tube *s* so as to cover the ports *t*, as shown in dotted lines in Fig. 3. A coupling ring *C* is screwed upon the upper part of the tube *s* so as to hold the said sleeve between the tube and the lower part of said ring.

The operation of said apparatus is as follows:

10 The ring *r'*, Fig. 2, is disposed in one of the notches *r²* in the rod *h*, so that when the chain *r* is stretched by the spring *g* the space within the tube *a* connected through the orifice *o* with the interior of the tube *b* shall have the requisite capacity. When the engine is set in operation, the vacuum produced in the suction conduit *f* will act upon the valve *i* and will raise said valve from the position shown in full lines to the position shown in dotted lines, Fig. 2. The piston *j* will rise and will close the inlet of the liquid fuel *c*, the lifting of the valve *i* will produce a partial vacuum in the inner portion of the tubes *a* and *b*, as these are connected by the conduit *d* with the suction conduit *f*.

In the succeeding stroke, when the suction of the engine ceases, the valve *i* will drop upon its seat, this position being shown in full lines in Fig. 2. The duct *c* is again uncovered, and as a partial vacuum is produced in the tubes *a* and *b*, the carburant will enter therein and will become partially converted into gas by impinging upon the spring *l*, the valve stem *i* and the walls of orifice *o*. In the following suction stroke of the engine the valve is lifted, the duct *c* is closed, and the whole of the carburant in the tubes *a* and *b* is withdrawn through the conduit *d* into said conduit *f*, the vaporization being completed when the carburant passes between the raised valve *i* and the walls of the tube *b*.

It is obvious that according to the position of the washer *r'* in the notches *r²*, i. e., according to the position of the cylinder *g* in the tube *a*, the capacity of the latter which communicates with the interior of the tube *b* will have a greater or less value, so that the volume of carburant within the tubes *a* and *b* will vary in proportion. For the same reason, the volume of carburant withdrawn when the valve *i* is lifted, represented by what is contained in the tubes *a* and *b* will vary in like manner. The amount of carburant which is to be withdrawn by the engine during each suction stroke can thus be regulated by properly adjusting the position of the piston *g*. Such adjustment varies the throw of the piston *g* and consequently the effective volume of cylinder *a*, so that as soon as the valve *i* closes, the suction produced by piston *g* under the influence of its spring *g* may be varied according to the position of ring *r'* along the piston rod *h*.

More or less fuel is drawn through *c* therefore, according to the length given to the stroke of piston *g* in cylinder *a*.

When the apparatus is used upon the engines of motor vehicles, the rod *h* is connected by suitable means with the accelerator pedal, so that according to the conditions of travel the driver will be enabled to vary the size of the space within the tube *a* and thus vary the amount of carburant supplied to the engine. In this case the chain *r* is nevertheless preferably maintained, and it serves to determine the maximum displacement of the piston *g* and hence the maximum fuel feed.

Air or similar comburents forming the fuel mixture are admitted in the following manner:

Under the action of the engine suction and the partial vacuum produced in the tube *f*, the cylinder *u* will rise, and the ports *v* will coincide respectively with the apertures *t* (position Figs. 1 and 3) and under these conditions the air will enter the cylinder *u* in the direction of the arrows, Fig. 3.

Should it be desired to increase the power of the engine and to reduce the amount of air in the fuel mixture, the sleeve *b* shown in dotted lines in Fig. 3 is mounted upon the tube *s* so as to wholly or partially close said apertures and to connect the tube *f* at another point along the same with an apparatus which, for instance, supplies pure oxygen.

I claim—

1. An automatic fuel inlet for internal combustion engines, comprising a chamber, means to adjust the volume of said chamber at will, means connecting said chamber with said fuel inlet, a valve for said inlet, a conduit for connecting said chamber with the intake of an engine, a valve in said conduit moved by the suction of the engine and connected to and arranged to actuate the aforementioned valve to obturate said inlet, whereby the engine will only aspirate the fuel contained in said chamber.

2. An automatic fuel feed device for internal combustion engines, comprising a chamber having a variable and adjustable volume, a second chamber connected therewith, a piston movable in the second chamber, a valve secured to said piston arranged to be lifted at each suction stroke of the engine whereby connection shall be made between the two chambers and the suction conduit, means admitting liquid carburant to said chambers and so disposed that the carburant inlet shall be closed by said piston when the said valve is lifted, a spring to return the valve to its seat when the aspiration of the engine ceases and means for the concurrent admission of air to the suction conduit of the engine.

3. An automatic fuel feed device for in-

ternal combustion engines, comprising a cylindrical tube, a piston movable therein, means for varying the position of the piston in the tube whereby the volume of the chamber can be regulated, a second tube connected with the first-mentioned tube, a piston movable therein, a valve secured to the same a duct for the admission of carburant within the latter tube, said duct being so disposed as to be cut off by the piston when the said valve is lifted, means for connecting the tube containing the valve with the suction conduit of the engine, a third tube connected with the suction conduit of the engine, apertures formed therein, a hollow cylinder movable in the said tube by the effect of the engine suction and ports formed in the hollow cylinder and cooperating respectively with

the apertures in the tube, whereby air shall be admitted into the suction conduit of the engine.

4. An automatic fuel inlet for internal combustion engines, comprising a cylinder, a tube connected thereto arranged for connection to the suction conduit of the engine and having a fuel inlet, a piston valve in said tube controlling said inlet, a valve operated by suction of the engine and connected to said piston valve for unison operation, a spring-retracted piston in said cylinder and means to adjust the stroke of the piston at will to fix the operating volume of said cylinder at will.

In testimony that I claim the foregoing as my invention, I have signed my name hereto.

AGÉNOR MARCHANT, JR.
